(57) **CLAIM**

The ornamental design for a wheel cap, as shown and described.

DESCRIPTION

FIG. 1 is a perspective view of the wheel cap exploded away from a wheel shown in broken lines which forms no part of the claimed design;

FIG. 2 is an elevational view of the wheel cap of FIG. 1; FIG. 3 is a top plan view from the top of FIG. 2;

FIG. 4 is a bottom plan view, opposite that of FIG. 3; FIG. 5 is an end elevation view of FIG. 2 taken from the left of FIG. 2 looking towards the left end of the wheel cap, of which the opposite end is a mirror image; and,

FIG. 6 is a sectional view taken along lines 6-6 in FIG. 2, depicting the outer surface shown in FIG. 2 as convex and the opposite inner surface as concave.

The wheel cap is shown in an enlarged scale in FIGS. 2-6. The broken line showing of portions of the logo of FIGS. 1 and 2 depict environmental subject matter only and forms no part of the claimed design.
